REGULATING SYSTEM FOR PUMPS

Filed Sept. 4, 1945

UNITED STATES PATENT OFFICE

2,475,248

REGULATING SYSTEM FOR PUMPS

Orlo C. Norton, Erie, Pa., assignor of twenty-five,
per cent to William J. Shea, Erie, Pa.

Application September 4, 1945, Serial No. 614,218

10 Claims. (Cl. 230—31)

1.

This invention relates generally to pumps and compressors, and more particularly to regulating means therefore.

In all devices of this character made according to the teachings of the prior art, and with which I am familiar, the output of air or gas compressors is usually controlled by regulators which throttle the intake or hold the intake valves open or use of clearance pockets resulting in low efficiency and abrupt changes in load or the capacity of constant speed liquid pumps is usually controlled by regulators which hold open the suction valves, stops the machine, or it bypasses the liquid back to the suction side of the pump.

It is, accordingly, an object of my invention to overcome the above and other defects in present regulators for fluid pumps and the like and it is more particularly an object of my invention to provide regulating means for a fluid pump or the like which is simple in construction, economical in cost, efficient in operation, and easy to install, operate, and maintain.

Another object of my invention is to provide regulating means for a fluid pump or the like which delays closing of the intake valves during the compression stroke of a pump to regulate the capacity.

Another object of my invention is to provide regulating means for opening the suction valves of a pump during the intake and compression stroke resulting in better volumetric efficiency.

Another object of my invention is to provide regulating means for a fluid pump or the like wherein a maximum charging efficiency is obtained with a light super-charging.

Another object of my invention is to provide regulating means for a fluid pump or the like wherein the piston is cushioned, the thermal efficiency is increased, and no throttling takes place at any time.

Another object of my invention is to provide regulating means for a pump wherein fluid under pressure is admitted under the intake valve to open it during the suction stroke and during none, or all, of the pumping or compression stroke.

Other objects of my invention will become evident from the following detailed description, taken in conjunction with the accompanying drawings, in which:

Fig. 1 is a longitudinal vertical sectional view of a pump member with my novel regulating system connected therewith.

Fig. 2 is a diagrammatic view of a pump member with a modified form of regulating system, and

2.

Fig. 3 is a diagrammatic view of a pump member with another form of regulating system.

Referring now to the drawings, Fig. 1 shows a cylinder 1 having end members 2 and 3, inlet chamber 4 with inlet valves 5 and 6 leading to opposite ends of the cylinder 1 and an outer or discharge chamber 7 connected with a receiver 33, with outlet or discharge valves 8 and 9 leading thereto from the cylinder 1. A reciprocating piston 10 moves in the cylinder 1 powered by a suitable prime mover (not shown).

Small tubular bleeder tubes 11 and 12 are disposed in the end members 2 and 3 with check valve members 13 and 14 lead to a regulating cylinder 15 and to connecting tubular members 16 and 17. Tubular members 16 and 17 lead to the underside of diaphragms 18 and 19 disposed in inlet valves 5 and 6. Upwardly extending members 20 and 21 on the diaphragms 18 and 19 extend through passages 22 and 23 and sealing members 24 and 25 are disposed on the upper ends of the projecting members 20 and 21 to seal passages 22 and 23 when the piston 10 moves in the cylinder 1. Stop members 26 and 27 limit the movement of the diaphragms 18 and 19 and projecting members 28 and 29 with sealing members 24 and 25.

The regulating cylinder 15 has centrally disposed apertures 30 through which the bleeder tubes 11 and 12 extend. The bottom end of the cylinder 15 has a threaded portion 31 to which is engaged a threaded tubular member 32 leading to the receiver 33. The upper end of the cylinder 15 has a threaded portion 34 engaged by a threaded cock member 35 to permit bleeding of air from the cylinder 15 and connecting bleeder tubes 11 and 12. A piston 36 is disposed in the cylinder 15 below the apertures 30 and is urged to the bottom of the cylinder 15 by a spring 37. Different strength springs may be disposed in cylinder 15 to require more or less pressure to move the piston 36 upwardly in the cylinder 15 or regulating means (not shown) may be provided to regulate the pressure of the spring 37.

In operation, the piston 10 is reciprocated in the cylinder 1 and a small amount of fluid is forced alternately through the tubular members 11 and 12 and immediately bled off by the cock member 35. The pressure in the receiver 33 will continue to rise until a predetermined pressure is reached. Air under pressure will pass through the tubular members 32 from the receiver 33 to move the piston 36 upwardly against the force of the spring 37 to close the apertures 30 in the cylinder 15. Air will then pass from the bleeder

tubes 11 and 12 alternately to the tubular members 16 and 17 to force the diaphragms 18 and 19, projecting members 20 and 21, and sealing members 24 and 25 upwardly to open the passages 22 and 23 during the intake stroke and on further rise of pressure in the cylinder 1, during all, part or none of the compression stroke of the piston 10 depending on air demand. The air in the ends of the cylinder 1 completely fills the area thereof between the piston 10 and the ends of the cylinder 1 in that the cylinder 1 is always completely filled on the suction or intake stroke of the piston 10 and only a predetermined part of the air is retained in the cylinder 1 for a given load. It will be evident that the charges of air to the oppositely disposed valves 5 and 6 are in step with the reciprocating piston 10 and they operate alternately with the reciprocation of the piston 10.

Fig. 2 shows a slightly modified regulating member. A cylindrical member 40 has bleeder tubes 41 and 42 with check valves 43 and 44 leading therein through apertures 45 from opposite ends of a cylinder 46 similar to the cylinder 1 shown in Fig. 1. Tubes 47 and 48 lead to diaphragms controlling intake valves (not shown) in the cylinder 46 and to apertures 49 in the cylindrical member 40. The lower end of the cylindrical member 40 has a threaded portion 50 for receiving the threaded tube 51 leading to a receiver (not shown) as in Fig. 1. An air cock 52 is disposed in the other end of the cylindrical member 40 to open it to air and to free fluid therefrom. A piston 53 having a grooved portion 54 and shoulder 55 on the upper end thereof and urged downwardly by the spring 55 is disposed for movement in the cylindrical member 40. A screw member 56 prevents rotation of the piston 53 by engaging the slot 57 in the piston 53.

The piston 53 has a laminated core 58 which is energized by the coil 60 which surrounds the cylindrical member 40. Electrical conductors 61 and 62 lead to coil 60. Switching means (not shown) connected and operable with a motor (not shown) causes energization of the coil 60 upon changes in the motor output. The motor is used for operating the piston on the piston rod 63 in the cylinder 46.

In operation, when the pressure in the receiver (not shown) reaches a predetermined pressure, the piston 53 is moved upwardly against the force of the spring 55 to close the bleeder apertures 45 and thereby prevent fluid from entering the cylinder 46 to pass to the tubular members 47 and 48 leading to diaphragms in the intake valves (not shown). The fluid normally passes from the bleeder tubes 41 and 42 alternately to the tubes 47 and 48 and to the diaphragms in the intake valves (not shown) in the cylinder 46 to hold the intake valves open during the suction stroke and during all, some, or none of the compression stroke. The shoulder 55 of the piston 53 acts as a throttle to the fluid passing from the bleeder tubes 41 and 42 to the tubes 47 and 48. This throttling will take place on a heavy or light load in that the piston 53 would be located in the bottom of the cylindrical member 40 and the upper shoulder 55 of the piston 53 would be directly opposite the apertures 49 leading to the tubes 47 and 48 which in turn lead to the intake valves (not shown) in the cylinder 46. The threaded cock 52 may be used to increase or decrease the spring pressure. It will be seen that this design provides a very economical regulating member for a compressor under heavy loads. The coil 60 may cause the upward movement of the

piston 53 through magnetic force when it is energized in accordance with any predetermined variation in output of an electric motor.

Fig. 3 shows a cylindrical member 70 exactly the same as the cylindrical member 40 shown in Fig. 2. The bleeder tubes 71 and 72 from the cylinder 73 have resilient members 74 and 75 inserted in housings 76 and 77, which give resiliency to fluid causing it to open and hold open intake valves 78 and 79 after flow from cylinder 70 has ceased at the completion of the compression or pumping stroke. It will be seen that I have shown bellows as the resilient members 74 and 75 although any suitable means may be used. Bleeder lines 80 and 81 lead to the cylindrical members 70 from each end of the cylinder 73 as in Figs. 1 and 2.

In operation, fluid enters the cylindrical member 70 through bleeder tubes 80 and 81 from alternate ends of the cylinder 73 and passes through the bleeder lines 71 and 72 to the resilient members 74 and 75 and to the intake valves 78 and 79. The resilient members 74 and 75 are compressed and after the fluid flow has ceased, pressure will be exerted by the resilient members 74 and 75 to hold the intake valves 78 and 79 open a predetermined length of time.

In all of these designs there is no passage from one end of cylinder to the other, then there can be no by-passing.

It will be seen from the foregoing that I have provided a practical and efficient means for regulating a fluid pump with minimum of moving parts, which permits fluid compression in accordance with demand, improved starting efficiency, a more uniform load, a cushion at the end of the piston stroke, improved thermal efficiency, and without throttling of the intake or valves.

Various changes may be made in the specific embodiment of my invention without departing from the spirit thereof, or from the scope of the appended claims.

What I claim is:

1. A regulator for a fluid pump having a cylinder, a reciprocating piston therein, and inlet and outlet valves on opposite ends of said cylinder and a receiver connected therewith comprising bleeder tubes in each end of said cylinder, diaphragms for opening and closing said intake valves connected with said bleeder tubes, a regulating cylinder connected with said receiver and said bleeder tubes, and a spring urged piston adapted to close said bleeder tubes whereby said diaphragms are moved alternately by pressure created by movement of said reciprocating piston to hold open said intake valves during any predetermined part of the movement of said reciprocating piston.

2. A regulator as set forth in claim 1 wherein check valves are disposed in said bleeder tubes.

3. A fluid compressor comprising a cylinder, a reciprocating piston therein, inlet and outlet chambers adjacent said cylinder, inlet and outlet valves on each end of said cylinder between said cylinder and inlet and outlet chambers, a fluid receiver connected with said outlet chamber, bleeder tubes on each end of said cylinder, diaphragm members for opening and closing said intake valves connected with said bleeder tubes, a regulating member connected with said bleeder tubes and said receiver, and means operable by predetermined pressures in said receiver for closing said bleeder tubes whereby said diaphragm members are alternately moved by the pressure in said bleeder tubes created by said reciprocating

piston to open said intake valves during any part of the movement of said reciprocating piston.

4. A fluid compressor system as set forth in claim 3 wherein check valves are disposed in said bleeder tubes.

5. A fluid compressor system as set forth in claim 3 wherein said last mentioned means is a spring-urged piston in said regulating member.

6. A fluid compressor system as set forth in claim 3 wherein a cock is disposed in said regulating member to open said member to free the fluid therein.

7. A regulator for a fluid pump having a cylinder, a reciprocating piston therein, inlet and outlet valves and a receiver connected therewith comprising bleeder tubes on opposite ends of said cylinder, diaphragms for regulating the opening and closing of said intake valves, tubes leading to said diaphragms; and a regulating member connected with said receiver having spaced, oppositely disposed apertures for receiving said bleeder tubes and said tubes leading to said diaphragms, and a grooved spring-urged piston in said regulating member adapted to normally throttle fluid passing to said tubes leading to said diaphragms and also adapted to close said bleeder tubes upon a predetermined pressure in said receiver.

8. A regulating member as set forth in claim 7 wherein said regulating member has an elec-

trical coil disposed therearound to move said piston upwardly upon energization of said coil.

9. A regulator for a fluid pump having a cylinder, a reciprocating piston therein, inlet and outlet valves, and a receiver comprising bleeder tubes disposed in opposite ends of said cylinder, a regulating member connected with said receiver and said bleeder tubes adapted to close said bleeder tube on a predetermined pressure in said receiver, tubes connecting said regulating member and said intake valves to alternately hold said valves open, and resilient means in said tubes adapted to hold said intake valves open after flow of fluid from said regulating member ceases.

10. A regulator as set forth in claim 9 wherein said resilient means comprises compressible bellows.
